UNITED STATES PATENT OFFICE.

CHARLES MORLET, OF LOCLE, SWITZERLAND.

WATCH-BARREL.

SPECIFICATION forming part of Letters Patent No. 617,115, dated January 3, 1899.

Application filed August 22, 1898. Serial No. 689,212. (No model.)

To all whom it may concern:

Be it known that I, CHARLES MORLET, watchmaker, of Locle, Switzerland, have invented certain new and useful Improvements 5 in Watch-Motors, of which the following is a specification.

The invention consists of an improved construction of the motors of watches, the purpose of which is to improve the good working 10 of the said motor.

The invention is shown in the accompanying drawings, in which—

Figure 1 is an axial section of the motor and of a portion of the spring-barrel bridge. Fig. 15 2 is a plan view of the inner face of the winding-up wheel. Fig. 3 is a plan view of the outer face of the same wheel. Figs. 4 and 5 show, separately, detached portions of the device.

20 In all the figures the same letters refer to the same parts.

A is the spring-barrel bridge, upon which is provided a ratchet mechanism of any well-known construction, (not shown in the drawings,) which prevents the rotation of the 25 wheel B in one direction.

C is the axis, to which is fixed the inner end 30 of the mainspring. The square portion c of the said axis C bears the said wheel B, fixed thereto by means of a screw c'.

D is a steel ring having a shoulder located 35 in the bridge A and bearing with its largest face upon the spring-barrel E, with which it is rotating. A pin d, traversing the ring D parallelly to the axis of the same and engaging

a suitable hole of the cover of such barrel, causes the said ring D to rotate with the spring-barrel E. Moreover, the said pin d enters a circular groove b' of the wheel B and acts (upon once at each revolution of the 40 spring-barrel relatively to the wheel B or in-verse) one tooth of the stop-wheel F, located in a recess b² of the said wheel B. The lat-ter is, moreover, provided with an out-cut b³, which allows one to act upon the stop-wheel F 45 by means of any suitable tool whatever while the wheel B is in its place.

The spring-barrel E is held in its place on its axis C by means of the usual core G.

In those watches which are not provided 50 with a stopping device of the mainspring axis or barrel the same device as described will be applicable, the stop-wheel F being then dis-pensed with and also the grooves b' and b² of wheel B.

Having thus fully described my invention, 55 I claim—

An improved motor for watches, having a steel ring D provided with a pin d, in combi-nation with a wheel B having a circular groove 60 b' for the passage of the end of said pin d and a stop-wheel F located in a recess b² and en-gaging with the said end of the pin d.

In testimony that I claim the foregoing as my invention I have signed my name in pres-65 ence of two subscribing witnesses.

CHARLES MORLET. [L. S.]
